UNITED STATES PATENT OFFICE

97,220

DESIGN FOR A PHONOGRAPHIC TRANSCRIBING MACHINE

Leland Stanford Briggs, Douglaston, N. Y., and
Leland D. Norton, Bridgeport, Conn.

Application June 17, 1935, Serial No. 57,302

Term of patent 14 years

To all whom it may concern:

Be it known that we, Leland Stanford Briggs, a citizen of the United States, residing at Douglaston, in the county of Queens and State of New York, and Leland D. Norton, a citizen of the United States, residing at Bridgeport, in the county of Fairfield and State of Connecticut, have invented a new, original, and ornamental Design for Phonographic Transcribing Machines, of which the following is a specification, reference being had to the accompanying drawing, forming part thereof.

Fig. 1 is a right front corner perspective of a transcribing machine, showing our new design, and

Fig. 2 is a left rear corner perspective of the same machine.

We claim:

The ornamental design for a phonographic transcribing machine, as shown.

LELAND STANFORD BRIGGS.
LELAND D. NORTON.
